UNITED STATES PATENT OFFICE.

CHARLES A. DIXON, OF NEWBURG, NEW YORK, ASSIGNOR TO ROBERT WHITEHILL, OF SAME PLACE.

STEAM-CONDENSER.

SPECIFICATION forming part of Letters Patent No. 276,526, dated April 24, 1883.

Application filed February 17, 1883. (No model.)

To all whom it may concern:

Be it known that I, CHARLES A. DIXON, of Newburg, county of Orange, State of New York, and a citizen of the United States, have 5 invented an Improved Steam-Condensing Apparatus, of which the following is a full, clear, and exact description, reference being had to the accompanying drawings, forming part of this specification.

10 My invention relates to an apparatus for condensing live or exhaust steam, particularly for the purpose of making distilled or fresh water; and my invention consists in a steam-condenser composed of the several specific 15 parts, constructed, placed relatively to each other, and combined to operate substantially as hereinafter particularly set forth.

Figure 1 is a vertical central sectional view of a condenser embodying my invention. Fig. 20 2 is a cross-section on the line $y-y$, Fig. 1; and Fig. 3 is a cross-section on the line $x-x$, Fig. 1.

25 My condenser is composed of five principal and distinct parts—namely, three cylinders concentrically arranged, a base-plate, and a head-sheet or top—and these parts are put together and combined to constitute the condenser, as hereinafter particularly set forth.

30 A is the exterior cylinder. B is the exteriormost cylinder, and C is the cylinder intermediate A and B. D is the base-plate, and E is the head-sheet or top plate of the apparatus. The cylinder A has the greatest diameter, as shown, and is mounted on the base-plate D, to which it may be bolted, as shown; and it 35 has a core or overflow-conduit formed on one side of it, as shown at a , with a discharge-opening at a' into said conduit, at or near the bottom of said cylinder, and said conduit having an egress-port at a'' , near the top of said cylinder, as shown. Within said cylinder A, and concentric to the same, is placed the cylinder C, mounted on the base D by means of bolts passing through flange c , and arranged to inclose and constitute a space or chamber between it and cylinder A, and extending upward toward but not to the same height as the top line of cylinder A. B, the interior cylinder, is arranged concentrically within C, so as to constitute a space or chamber between it 45 and C, and it is suspended within C by means of a top edge flange, b , lapped to a flange, c' ,

on upper edge of C. The lower end of B is formed with a bottom plate or bead, b' , as shown, and this lower end extends downward toward but not to the line of the bottom edges of cylinders A and C, thus constituting a space or chamber between the lower face of said end b' and upper face of base-plate D, as shown. In this plate b' of B are set the tubes b^2 , opening through said plate, as shown; and said tubes extend thence upwardly longitudinally of said cylinder B, to and through the head-sheet or top E. This head-sheet E is secured in place by bolts passing through its rim and a flange, a^3 , on upper edge of A. The tubes 60 may be expanded, or may be screwed into their seats. An outlet-pipe, m , with a wide mouth to inclose the open upper ends of the tubes, is bolted upon the top of the head-sheet E, as shown. The steam-inlet pipe is seen at F, 70 passing through cylinder A, near the top of the apparatus, where a stuffing-box, f , may be provided, and extending through C and opening into the space or chamber between B and C, as shown. The condensing-water inlet is at 75 G, passing up through base-plate D and into cylinder B, through the bottom b' thereof, the condensing-water outlet being at $a-a'$, as herefore described. Upon the under side of base-plate D, and opening through the same, is the 80 conduit for the water of the condensed steam.

It is evident that the three cylinders, the base-plate, and head-sheet may all be made of cast metal in an inexpensive manner, the cylinder A having the core $a-a'$ cast with it, the 85 cylinder B having its bottom b' cast with it, and the base-plate D having the conduit H cast on it, as shown, and that the several parts, by means of their flanges and bolts, as described, may be readily put together and combined to constitute the condenser, the tubes b^2 being introduced as described.

The steam enters at F, and passes through and fills the spaces or chambers marked s , and thence through the tubes b^2 , while the cold condensing-water entering at G fills the cylinder B around the tubes, rises and flows over the top edge of B, and thence falls into and fills the space between A and C, thus circulating through all the spaces and chambers 100 marked w , and finally passing out at a' to conduit a , and thence out at a'' . The steam as it

condenses falls upon the base-plate D, and the water runs out through H, while the steam which fails to condense escapes at m.

By means of my apparatus the water of the condensed steam is kept free from impurities, such impurities being carried off at m with the uncondensed steam, while at the same time the structure of the apparatus secures a large surface for condensation. When it is desired, 10 for any reason, to examine the interior of the apparatus, or to take the apparatus apart, it may be done much more readily, owing to the simplicity of its structure, than in condensers as usually constructed.

15 What I claim as new, and desire to secure by Letters Patent, is—
A steam-condensing apparatus composed of

the outer cylinder, A, inner cylinder, B, and intermediate cylinder, C, arranged concentrically of each other, and the base-plate D and 20 head-sheet or top E, thus constituting the steam-chambers and condensing-water chambers w, said cylinder A having formed on it the core or water-outlet a a', said cylinder B having the bottom b' and carrying tubes b², 25 and said base-plate D having outlet H, together with steam-inlet F, water-inlet G, and steam-outlet m, all constructed as specified, and combined to operate as and for the purpose described.

CHAS. A. DIXON.
